SEWING MACHINE

Alf F. Cederquist, St. Louis, Mo.

Application October 22, 1934, Serial No. 749,355

5 Claims. (Cl. 112—215)

This invention relates to sewing machines and more particularly to feed dogs for post sewing machines. Heretofore this type of sewing machine employed a feed dog comprising an elongated member having its lower end fixed to a link pivotally and slidably mounted on the post and having the face of its upper end serrated and adapted to engage and advance the work pressed thereagainst by the presser wheel. As this serrated face wore out quickly, it was necessary at frequent intervals to detach said feed dog and resharpen the teeth or serrations. Thus new adjustment of the feed dog was necessary at each sharpening operation and the entire member had to be discarded in a very short time due to these numerous sharpenings.

One of the objects of the present invention is to provide a two-part feed dog, namely, a member fixed to the operating link and a member having a serrated face and detachably mounted on the first member, said serrated face member being disk-shaped or polygonal shape and being axially mounted on said support member and adjustable to present any one of the peripheral serrated portions in working position.

Another object of the invention is to provide a feed dog assembly having a detachable serrated face member which can be detached and replaced with a new one without disturbing the connection between the support member and the actuating link.

An additional object of the invention is to provide a feed dog construction of the character described which is efficient in operation, has a long period of usefulness and reduces the cost of maintenance of the sewing machine.

With these and other objects in view, my invention consists of certain novel features of construction and arrangement of parts, hereinafter more fully described and claimed, and illustrated in the accompanying drawing, in which—

Figure 1 is a fragmental side elevational view of a post sewing machine showing part of the head and some of the mechanism for actuating the feed dog.

Figure 2 is an enlarged top plan view of the feed dog assembly.

Figure 3 is a front elevational view of same with the operating link broken away.

Figure 4 is a vertical cross section taken through the feed dog assembly.

Figure 5 is a detail view of a modified form of the feed dog member.

Figure 6 is a horizontal cross section taken on line 6—6 of Figure 3.

Referring by numerals to the accompanying drawing, 10 represents a head of a post sewing machine and 11 the post on which the feed dog assembly is mounted. The head 10 is provided with the usual needle bar 12 having a needle 14 and a presser bar 15 having a roller presser 16.

The post 11 has pivotally and slidably mounted thereon by means of a pivot 17 a dog actuating device 18. This device includes a vertically disposed link 19 having a longitudinally disposed slot 20 for receiving the pivot 17. This pivot consists of a horizontally disposed screw or pin 21 fastened to the post and a block 22 loosely mounted on said pin and occupying said slot 20. The width of the block is substantially the same as that of the slot but the length of the latter is greater so that said link 19 is free to move longitudinally a suitable distance.

The lower end of the link 19 is connected to suitable operating mechanism which imparts to the upper end of said link movement indicated by arrows in Figure 1. This mechanism includes a pair of rock shafts 24 and 25 arranged below and in spaced-apart relation with each other and the lower end of said link. Fixed to shaft 25 is a vertically projecting rock arm 26 to the upper end of which is pivotally connected the outer end of a horizontally disposed arm 27. This arm extends toward shaft 24 past the lower end of said link 19 and is pivotally connected to said end, as indicated at 28. Thus the actuation of said rock shaft 25 imparts rocking or pivotal movement to said link, with the pin 21 as the axis.

The shaft 24 has fixed thereon one end of a rock arm 29 which extends horizontally toward the outer end of arm 27 and carries a pin or screw 30 on which is pivotally mounted a block 31. The outer end of arm 27 is bifurcated to form a horizontally disposed slot 32 and the block 31 has a sliding bearing therein. Thus the actuation of rock shaft 24 rocks arm 29 and through the connection thereof with arm 27 imparts to said link 19 longitudinal movement.

This longitudinal movement is in time relation with the oscillating or rocking movement so that the cycle of movement of the upper end of said link is to the right (restoring movement), then upwardly, then to the left (work advancing movement), and then downwardly to repeat the cycle of operation, as indicated in dotted lines and arrows in Figure 1.

A needle plate 33 is fixed to the upper end of post 11 and is provided with a slot 33a. The construction hereinbefore described is one commonly used in post sewing machines.

My invention relates to the feed dog assembly. Whereas, heretofore the feed dog or serrated face was formed on the upper end of the member fixed to link 19, I provide a feed dog member 34 which is detachable from the support member 35, which latter is fixed to the upper end of link 19.

This support member 35 has a shank portion or lower end 35a which is reduced in width and is provided with a longitudinally disposed slot 36 through which extends a screw 37. This screw is screw-seated in the upper end of link 19 and serves to hold said member 35 in fixed position on said link, while slot 36 permits longitudinal adjustment of said member 35. In order to hold said member 35 in proper longitudinal alignment with said link, the upper end of the latter is provided with a key or longitudinally disposed shoulder 19a and the shank 35a is formed on one side with a key-way or slot 35b for receiving said key 19a. The upper end of member 35 is formed on one side with a circular recess 38 which is of sufficient diameter to cut away the central portion of the upper end of said member, as indicated at 38a. Fixed in said recess by a set screw 39 is the feed dog member 34 which, in the instant case is disk-shaped and has its peripheral surface serrated, as indicated at 40. The diameter of this feed dog 34 is such that the upper portion thereof projects outwardly through the opening 38a, thereby disposing the serrated face of said upper portion above the upper end of member 35 in working-engaging and advancing position. As member 35 is thicker than the thickness of disk 34, the upper end of said member 35 is cut away as indicated at 41, so that only the upper portion of member 34 and the upper ends of the reduced side portions of member 35 extend upwardly through the slot 33a in needle plate 33. The inner side of the upper end of member 35 is formed concave, as indicated at 42, to conform to the chamber in post 11, which chamber is round in cross section and contains the loop forming mechanism (not shown). The central portion of the shoulder 41 is rounded or tapered downwardly as indicated at 41a, in order to eliminate a flat horizontal surface in the path of the needle and prevent breakage of the latter in case the point of the needle is bent or forced thereagainst. By rounding this portion the point of the needle is deflected or guided downwardly against the concave face 42 without causing breakage of the needle.

The roller presser is disposed above the feed dog member 34 and the work is clamped therebetween and is advanced by the actuation of said feed dog through the oscillating and longitudinal movement of link 19.

When the exposed portion of the feed dog 34 is worn out, set screw 39 is loosened to permit partial rotation of said member 34 so as to permit a new serrated surface to be placed in operating position. When the entire serrated peripheral surface of the feed dog has been worn out, the disk 34 can be removed and replaced by a new one or the old one can be reshaped.

In the form shown in Figure 5, the feed dog member 44 is of octagonal shape, thereby providing eight serrated faces 45 for use.

The work engaging member being formed separate from the supporting member, it can be replaced with a new one without removing or replacing the support member. Furthermore, the work engaging member can be case-hardened and when worn out the temper can be drawn out and

the serrated face thereof sharpened and then again case-hardened without requiring said support member to be subjected to these operations.

By forming the work engaging member of a circular shape or a polygonal shape, a large serrated surface is provided so that said member can be adjusted to present a new peripheral portion into work-engaging position as the old one is worn out.

The opening in the needle plate is wide enough to allow the upper portion of the work engaging member and of the upper ends of the reduced side portions of the support member to project upwardly therethrough. The needle in moving into the upper end of post 11 to cooperate with the loop forming mechanism operates through a needle opening in said needle plate. When the point of the needle is bent accidentally the corresponding side of the work engaging member and of the support engage the deflected point and guide it, and by virtue of the tapered or rounded portion on said support the needle is forced back to its normal position, thereby preventing breakage thereof.

Thus it will be seen that my invention not only increases the life and usefulness of the work-engaging member but also effects a great saving by reducing breakage of needles.

I claim:

1. In a sewing machine of the character described, the combination with a post and a vertically disposed link pivotally and slidably mounted thereon, of a feed dog device comprising a vertically disposed support member fixed to the upper end of said link, and a feed dog member 35 detachably secured to said support member, a serrated perimeter on said feed dog member, said feed dog member being positionable on said support member to present any portion of its serrated perimeter in work engaging and advancing position.

2. In a sewing machine of the character described, the combination with a post and a vertically disposed link pivotally and slidably mounted thereon, of a feed dog construction comprising a vertically disposed support member detachably fixed to the upper end of said link, a feed dog member arranged in juxtaposed relation with the upper end of said support member with its upper portion extending above the top of said support member into work engaging position, said feed dog member having its perimeter provided with a serrated surface, and means for securing said feed dog member axially on said support member whereby said feed dog member can be turned on its axis to present any portion of its serrated surface in work engaging and advancing position.

3. In a sewing machine of the character described, the combination of a post, a vertically disposed link pivotally and slidably mounted thereon, a vertically disposed support carried by the upper end of said link, a feed dog fixed to the upper end of said support with a portion disposed above the upper end of said support in work engaging and advancing position, said feed dog having its perimeter formed with a serrated face, and means for holding said feed dog in fixed relation with said support, said means being releasable to permit adjustment of said feed dog and bring any portion of the serrated perimeter thereof in work engaging position.

4. In a post sewing machine, the combination with a post and a vertically disposed link pivotally and slidably mounted thereon, of a support fixed to the upper end of said link, a feed dog fixed to

said support and having a portion projecting above the upper end of said support for engaging and advancing the work, said feed dog being disk-shaped and having its periphery provided with a serrated surface, and means for securing said feed dog axially to said support whereby said feed dog can be adjusted to move a fresh portion of its peripheral serrated face into work engaging position.

10 5. In a post sewing machine, a feed dog device comprising a vertically disposed link mounted for oscillating and reciprocating movement, a support

fixed to the upper end of said link, a disk having its periphery provided with a serrated surface, and a set screw for securing said disk in a fixed position on said support with the upper portion of said disk disposed above the upper end of said support in a work engaging and advancing position, said set screw being releasable to permit adjustment of said disk to bring a fresh portion of the peripheral serrated surface thereof into work engaging position.

10

ALF F. CEDERQUIST.
